UNITED STATES PATENT OFFICE.

GEORGE A. JOHNSON, OF CHICAGO, ILLINOIS, ASSIGNOR TO WILLIAM H. MINER, OF CHAZY, NEW YORK.

ROLLER SIDE BEARING.

1,290,218.

Specification of Letters Patent.

Patented Jan. 7, 1919.

Application filed March 12, 1918. Serial No. 221,903.

To all whom it may concern:

Be it known that I, GEORGE A. JOHNSON, a citizen of the United States, residing at Chicago, in the county of Cook and State 5 of Illinois, have invented a certain new and useful Improvement in Roller Side Bearings, of which the following is a full, clear, concise, and exact description, reference being had to the accompanying drawings, 10 forming a part of this specification.

This invention relates to improvements in roller side bearings.

One object of this invention is to provide an anti-friction roller side bearing, more 15 especially adapted for railway cars, the side bearing being so designed that the anti-friction roller will return to normal position under the influence of gravity after each actuation with a minimum amount of 20 friction.

Another and more specific object of the invention is to provide an anti-friction roller side bearing wherein the anti-friction roller is suspended on floating runways but with 25 the parts so arranged that when the side bearing is brought into action, the roller is placed under direct compression without imposing any load on the journals or trunnion supports.

30 In the drawing forming a part of this specification, Figure 1 is a vertical, sectional view, taken transversely of the body and car bolsters of a railway car and showing my improvements in connection therewith. Fig. 2 is a vertical, sectional view, taken substantially on the line 2—2 of Fig. 1. And Fig. 3 is a detail perspective of one of the floating runways.

35 In said drawing, 10 denotes a portion of a truck bolster of a car and 11 a portion of an opposed body bolster, it being understood that my improved side bearing is applied in the usual manner at the ends of the bolsters on each side of the center pin by 40 which the bolsters are connected.

45 As shown, the improved side bearing includes a base or retaining member A, an anti-friction roller B, runways C—C and springs D—D.

50 The retaining member A is preferably in the form of a casting having a lower horizontal bearing wall 12, vertically extending end walls 13—13 and vertically extending spaced side walls 14—14. The casting may 55 be secured to the bolsters by any suitable

means, such as the rivets 15, which pass through ears or lugs 16 formed integrally with the casting A.

Each side wall 14 of the base casting A is recessed on its inner face, as indicated 60 at 17, the recesses being so formed as to provide downwardly facing shoulders 18—18 near each end thereof. A floating runway C is disposed in each of the recesses 17, each runway C being of a length to move 65 freely within the recess 17 but limited in its upward movement therein by engagement with said shoulders 18. Each runway C is of hollow formation and is adapted to have the free ends 19—19 of a bowed 70 spring D seated therewithin, as clearly shown by the dotted lines in Fig. 1. The bowed springs D bear at their bottom ends on the lower walls 20 of the recesses 17 and said springs are held against lateral displacement by any suitable means, such as the flanges 21.

The anti-friction roller B is preferably of solid cylindrical form having integral short trunnions 22—22 which rest upon the 80 upper faces of the runways C. The upper faces of the runways C are oppositely and upwardly inclined from the center thereof, as indicated at 23—23.

85 In actual practice, the roller B will be supported or suspended by the trunnions 22 from the floating runways C and out of engagement with the bottom bearing plate 12 and also out of engagement with the upper body bolster 11. The springs D need be of 90 only sufficient strength to sustain the weight of the roller B, and do not have any other function in returning the roller B to normal position other than elevating the runways C after the latter have been depressed and the 95 pressure removed from the roller. When the side bearing is brought into action, the roller B will, of course, be forced downwardly into engagement with the bottom bearing 100 12 and rolled to either side of normal, depending upon the relative movements of the body and truck bolsters. The dotted lines in Fig. 1 designate the position of the anti-friction roller B at the end of its travel to the right, as viewed in said figure. As 105 the roller B is moved to either side of normal, it is evident that the corresponding ends of the runways C will be depressed against the action of the light springs D. If the pressure is now removed from the roller B, 110

assuming the latter in the dotted line position shown in Fig. 1, the roller B will be elevated due to the expansion of the springs D and the roller will then return to normal central position under the influence of gravity since the trunnions 22 will roll down the inclined surfaces 23 of the runways.

With the construction above described, the anti-friction roller is placed under direct compression when in operation and the trunnions 22 and runways C are not required to sustain any of the load, as has heretofore been customary in various types of anti-friction roller side bearings. Furthermore, during the return of the parts to normal, the roller is left entirely free of engagement with either the bottom bearing 12 or the upper bolster 11 so that it can readily roll back to central position under the influence of gravity with a minimum of friction. As will be understood, the vertical height of the runways C is made such that the latter are never brought down into engagement with the bottom walls 20 of the recesses 17 so that the runways C and springs D can be made unusually light.

I claim:

1. In an anti-friction bearing, the combination with a retaining member, of floating runways yieldingly carried by said member, a lower bearing surface, and an anti-friction roller normally supported on trunnions bearing on said runways and out of engagement with said bearing surface, said runways being compressible to permit the roller to engage with said bearing surface when the bearing is in operation and thereby place the roller under direct compression, while the trunnions are free from load.

2. In an anti-friction bearing, the combination with a retaining member having an

integral bottom bearing wall and side walls, of runways having inclined upper surfaces mounted in the side walls of said member, an anti-friction roller having trunnions engaging said inclined surfaces of the runways, and spring means for normally holding said runways in elevated position and thereby the roller out of engagement with the bearing wall, said runways being compressible to permit the roller to engage said bottom bearing wall.

3. In an anti-friction bearing, the combination with a retaining casting having an integral bottom bearing wall and upstanding side walls, each of said side walls being recessed on its inner face and the recesses provided with upper shoulders, of a runway mounted in each recess and limited in its upward movement by said shoulders, a spring for supporting each runway in its uppermost position, each runway having its upper face inclined upwardly in each direction from the center thereof, and an anti-friction roller having trunnions supported by said runways, the anti-friction roller being normally held out of engagement with the bottom bearing wall of the retaining member, the runways being compressible as the roller is moved to either side of normal to permit the roller to engage said bottom bearing wall and adapted to elevate the roller when pressure is removed from the latter and thereby permit the roller to return to central position under the influence of gravity and while freely supported by said trunnions.

In witness that I claim the foregoing I have hereunto subscribed my name this 28th day of Feb., 1918.

GEORGE A. JOHNSON.
